(57) **CLAIM**

(30) **Foreign Application Priority Data**

The ornamental design for a medical information communication apparatus, as shown and described.

Dec. 13, 2002 (JP) 2002-034693

DESCRIPTION

(51) LOC (7) Cl. **24-01**

FIG. 1 is a top perspective view of a medical information communication apparatus of the present invention;

(52) U.S. Cl. **D24/107; D24/186**

FIG. 2 is a front view thereof;

(58) Field of Search D24/107, 186,

FIG. 3 is a rear view thereof;

D24/232; 600/306, 301, 483, 508; 128/903,

FIG. 4 is a side view thereof;

904

FIG. 5 is a side view thereof, opposite that shown in FIG. 4;

(56) **References Cited**

FIG. 6 is a top view thereof; and,

U.S. PATENT DOCUMENTS

FIG. 7 is a bottom view thereof.
